UNITED STATES PATENT OFFICE.

DAVID HEER, OF PHILADELPHIA, PENNSYLVANIA, ASSIGNOR TO WILLIAM SMITH, OF SAME PLACE.

DESIGN FOR AN ORNAMENTAL RING.

SPECIFICATION forming part of Design No. 15,489, dated October 28, 1884.

Application filed July 11, 1884. Term of patent 7 years

To all whom it may concern:

Be it known that I, DAVID HEER, a citizen of the United States, and a resident of Philadelphia, Pennsylvania, have invented or 5 produced a new and original Design for an Ornamental Ring, of which the following is a specification.

My design for an ornamental ring is fully shown in the accompanying drawings, Figure 1 representing the design in its preferred form, and Fig. 2 showing the design slightly modified, but retaining the main feature, which is the notching of the edges of the ring, both inside and outside of the same, so as to form polygonal facets *a*.

The ring shown in Fig. 2 is so notched that its entire surface is composed of these polygonal facets; but the ring shown in Fig. 1 has rows of facets alternating with a zigzag band, 20 *b*. Each of the notches in the edge of the ring is so shaped as to form two polygonal facets, one inclined in one direction and the other in the opposite direction.

I claim—

1. The within-described design for an ornamental ring, said design consisting of the ring having its edges, both inside and outside, notched and forming polygonal facets, as shown and described.
2. The design consisting of the ring with its edges, both inside and outside, notched and forming polygonal facets *a*, with alternating zigzag band *b*, as shown and described.
3. The design consisting of the ring having in its edges notches, each forming two reversely-inclined polygonal facets, as shown and described.

In testimony whereof I have signed my name to this specification in the presence of two subscribing witnesses.

DAVID HEER.
